UNITED STATES PATENT OFFICE.

JOHN MARTIN, OF BELLE VERNON, PENNSYLVANIA.

RAIL-JOINT.

No. 906,250.

Specification of Letters Patent.

Patented Dec. 8, 1908.

Application filed May 6, 1908. Serial No. 431,176.

To all whom it may concern:

Be it known that I, JOHN MARTIN, a citizen of the United States of America, residing at Belle Vernon, in the county of Fayette and State of Pennsylvania, have invented certain new and useful Improvements in Rail-Joints, of which the following is a specification, reference being had therein to the accompanying drawing.

- 10 This invention relates to rail joints, and my invention aims to provide a novel connection for the confronting ends of rails that can be safely used without employing splice bars, nuts and bolts as a fastening medium.
- 15 To this end, I have devised a rail joint that will permit of the confronting ends of two rails being easily and quickly connected together, the form of the connection preventing lateral displacement of one rail with relation to the other. In connection with the rail joint, I have provided positive and reliable means for at all times maintaining a metal-to-metal connection between the confronting ends of two rails, whereby the rails
- 20 can be used as electrical conductors for a current of electricity, this type of joint being essential in railway signaling where track circuits form a part of the signal system of a railroad.
- 25 My invention will be further considered hereinafter and reference will now be had to the drawing forming a part of this application, wherein

Figure 1 is a perspective view of the confronting ends of two rails constructed in accordance with my invention, and Fig. 2 is an elevation of the same, partly broken away and partly in section.

In the accompanying drawings, 1 and 2 designate rails having intermediate portions similar in cross section to the present type of rail. The rail 1 is reinforced by an enlargement 3 located at the end of said rail, and extending outwardly from the end of said rail

40 is a hook shaped tongue 4 corresponding in width to the web 5 of said rail. The lower edge of the tongue 4 is in a plane horizontal with the bottom side or base of a rail 1, while the top edge thereof has stepped inclines, 45 said inclinations being formed parallel with

one another to produce a projection or shoulder 7. The tongue 4 is provided adjacent to the rail 1 with an angularly disposed socket 8, said socket being formed at right angles to the innermost inclined surface of said tongue. 55 In the socket 8 is located a coiled spring 9, the object of which will presently appear.

The rail 2 is reinforced by enlargements 10, said enlargements increasing the width of the web portion 11 of said rail at one end thereof 60 and providing a sufficient clearance of material for the formation of a vertical groove 12 extending from the bottom or base of said rail to the head or tread thereof, the groove corresponding in width and length to that of 65 the tongue 4. The groove 12 corresponds in area to the tongue 4, and said groove has its roof or the material forming the top of the groove shaped to provide a depending projection or shoulder 13 adapted to interlock 70 with the projection or shoulder 7 of the tongue 4.

When the rails 1 and 2 are to be connected, the end of the rail 2 is placed downwardly over the tongue 4, although said rail 2 can be 75 moved longitudinally towards the rail 1, in which case the shoulder 13 will ride up the inclined edge of the tongue until it drops behind the shoulder 7, when the rails will be in position. With the rail 2 resting on the 80 tongue 4, the spring 9 is under tension, and irrespective of the vibrations of the rails 1 and 2, this spring maintains a positive contact between said rails having a current of 85 electricity.

While in the drawings forming a part of this application there is illustrated the preferred form of construction embodying the invention, it is to be understood that the elements therein may be varied or changed 90 without departing from the spirit of the invention.

Having now described my invention what I claim as new, is:—

The combination with rails, one of said 95 rails having an enlargement at the end thereof, a tongue carried by the end of said rail and corresponding in width to the web of said rail, said tongue having its upper edge provided with inclinations forming a projection, 100

said tongue having a socket formed therein adjacent to said rail, a coil spring mounted in said socket, the other of said rails having the web thereof enlarged and provided with a 5 groove corresponding in width and area to said tongue, said groove having the material forming the top thereof shaped to provide a depending projection and inclinations corre-

sponding to the inclinations and projection of said tongue.

10

In testimony whereof I affix my signature in the presence of two witnesses.

JOHN MARTIN.
